UNITED STATES PATENT OFFICE

RICHARD C. COUPLAND, OF DAYTON, OHIO

AMMUNITION FEED BOX AND BELT FOR MACHINE GUNS

Application filed April 4, 1927. Serial No. 180,862.

(GRANTED UNDER THE ACT OF MARCH 3, 1883, AS AMENDED APRIL 30, 1928; 370 O. G. 757)

The invention described herein, if patented, may be manufactured and used by or for the Government for governmental purposes without the payment to me of any royalty thereon.

The subject of this invention is an ammunition feed box and belt for machine guns.

The limitations imposed by the mounting of machine guns on aircraft and the necessity for rapidity of loading has led to the development of special types of ammunition boxes or magazines. Boxes of this character which are provided with cartridge feeding apparatus frequently become jammed and are accordingly objectionable.

The principal object of the present invention is to provide a light, water proof, inexpensive and expendable container which will serve both as a shipping carton and as a magazine and which may be quickly opened to permit loading of the gun.

With the foregoing and other objects in view, my invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of the invention is illustrated in the accompanying drawings, wherein:

Fig. 1 is a longitudinal sectional view of an ammunition box constructed in accordance with the invention;

Fig. 2 is a sectional view on the line 2—2 of Fig. 1;

Fig. 3 is a perspective view of the support.

Referring to the drawings by numerals of reference:

The ammunition box is in the form of a rectangular carton of water-proof card board or fiber board and is composed of the sides 5, bottom 6 and a sectional cover, the smaller section 7 arranged to overlap and be detachably secured to the larger section 8 by adhesively connecting it thereto. The smaller section 7 when removed provides an opening in

the cover through which the ammunition 9 may be taken out.

The ammunition which is placed in the box before attachment of the cover is carried in a belt 10 which may be either of fabric or metallic disintegrating link construction. The end or end link of the belt carries a tab 11 which is provided to facilitate introduction of the belt into the feedway of the gun. In the present instance the tab is flexible to enable the end of the belt to be positioned at the side of the box adjacent the feedway of the gun. An arrangement of this character, in addition to being convenient for opening the cover, as will be described hereinafter, is especially favorable when metallic belts are employed as the upper layer of the belt may be inserted in the gun along a practically straight line.

When the ammunition is in the box and the larger section 8 of the cover secured in place the tab is extended along the outer surface of said section and is preferably fixed thereto as by glueing. The smaller section 7 is then put in place and glued to the larger section 75 which it overlaps. Opening the box may be accomplished by pulling the tab which will disengage the smaller section of the cover and enable the belt to be withdrawn.

The box may be placed in position adjacent the feed way of the gun by dropping it into a support 12 secured to the gun and having a spring 13 for firmly retaining the box.

It is intended that the box may be loaded and sealed at the arsenal and when empty 85 may be thrown away.

I claim:

1. In combination, an ammunition feed box comprising a container having a cover consisting of overlapping sections detachably secured to each other and a belt having a flexible tab extending between the sections of the cover and detachably secured to one of said sections.

2. In combination, an ammunition feed box comprising a container having a cover consisting of overlapping sections detachably secured to each other, and a belt having a flexible tab extending between the sections of the cover,

3. In combination, an ammunition feed box comprising a container having a sectional cover and a belt within the box and having an end extending between the sections of the cover.
4. In combination, a container, a closure for the container having a detachably secured portion, and a flexible element carrying the contents of the container with an end extending through the closure adjacent to the detachable portion whereby movement of the element to withdraw the contents of the container will detach the portion of the closure.
5. In combination, a container, a closure for the container having a detachably secured portion and a flexible element carrying the contents of the container and housed therein to be withdrawn in one direction, said element having an end extending through the closure adjacent to the detachable portion and in a direction opposite to the direction of withdrawal.
6. The combination with a machine gun having a feed channel, of an ammunition box supported adjacent to the feed channel, a detachably secured closure for the box, and an ammunition belt housed in the box and having an end extending through the closure and directed away from the feed channel.

RICHARD C. COUPLAND.
